UNITED STATES PATENT OFFICE.

ERNEST L. MEYER AND ALFRED F. MEYER, OF HAYS, KANSAS.

FOLDING CRATE.

1,037,162.

Specification of Letters Patent. Patented Aug. 27, 1912.

Application filed March 2, 1912. Serial No. 681,267.

To all whom it may concern:

Be it known that we, ERNEST L. MEYER and ALFRED F. MEYER, citizens of the United States, residing at Hays, in the county of Ellis and State of Kansas, have invented 5 certain new and useful Improvements in Folding Crates, of which the following is a specification.

This invention relates to folding crates 10 and has for an object to provide a crate formed of two collapsible mating halves, the halves being adapted to be collapsed independently of each other, and the bottoms of the halves being hingedly connected together, 15 so that each half when folded may be then folded upon the mating half, whereby a compact oblong bundle is presented which may be stored in minimum space.

A further object of the invention is to 20 provide one of the halves with a sliding slat to permit of access to the interior of the crate when set up, the guides of the slat further forming attaching means for locking the tops of both halves together.

25 With the above objects in view the invention consists of certain novel details of construction and combination of parts herein-after fully described and claimed, it being understood that various modifications may 30 be made in the minor details of construction within the scope of the appended claim.

In the accompanying drawings forming 35 part of this specification:—Figure 1 is a plan view of the crate. Fig. 2 is an end elevation of the crate. Fig. 3 is a longitudinal sectional view taken on the line 3—3 Fig. 1. Fig. 4 is a cross sectional view taken on the line 4—4 Fig. 1. Fig. 5 is a plan view of the crate collapsed. Fig. 6 is an end elevation of the crate collapsed. Fig. 7 is a side elevation of the crate collapsed.

Referring now to the drawings in which like characters of reference designate similar parts, the crate is shown to comprise two 45 mating halves, each consisting of a bottom 10, a side 11 hingedly connected to a longitudinal strip 12 secured to the edge of the bottom, by hinges 13, similar ends 14 hingedly connected to the bottom by hinges 50 15, a partition 17 similar to the ends and hingedly connected to the bottom by hinges 18, and a cover 19 hingedly connected to the side by hinges 20, the latter permitting of the cover folding outwardly upon the side, 55 the strip 12 being of such height as to per-

mit of the side being folded flat upon the partitions and ends when the latter are collapsed upon the bottom.

The bottoms are hingedly connected together by hinges 21 which permit of the bottoms folding outwardly one upon the other after the sides have been collapsed so that an oblong flat bundle as shown in Figs. 5 and 6 is presented when the crate is collapsed.

65 For securing the cover, ends, and partition of each half in operative position, lugs 22 are embedded in the top edges of the ends and partitions and fit into suitable openings 23 formed in the cover. Each end is equipped with a lock consisting of a bolt 24 having an eye at one end which receives a pivot pin 25, and having a thumb nut 26 threaded on the opposite end, the bolt being adapted to be rocked upward and seat in a notch 27 formed in the adjacent end edge of the cover, a wear plate 28 being fixed to the cover and forming an abutment for the thumb nut when the bolt is rocked into operative position.

70 The side, ends, partition and cover of each half are preferably formed of skeleton structure equipped with wire mesh to ventilate the crate. To permit of access to the interior of the crate when in setup position, 75 a slat 29 is slidably fitted to the longitudinal free edge of the cover of one of the halves U-shaped guides 30 being terminally secured to said cover and slidably receiving the slat, the guides being all connected by a common strip 31. Secured to the free edge of the mating cover is a plurality of downwardly opening hooks 32 which hook over the common strip 31 and secure the covers 85 of both halves together.

95 To knock down the crate, the thumb nuts are first loosened, and the locking bolts rocked out of engagement with the covers. The covers are then rocked open and collapsed outwardly upon the related sides. 100 The ends and partitions are then collapsed upon their respective bottoms and the sides then collapsed inwardly upon the folded partitions and ends. Each half at this stage is completely collapsed 105 upon the respective bottoms. To complete the folding operation the bottoms are now folded outwardly one upon the other. For locking the parts in collapsed position, hooks 33 are pivotally secured to the end 110

edges of the covers, the hooks carried by each cover being of sufficient length to engage lugs 34 arranged upon the end edges of the bottoms of the mating halves as clearly shown in Fig. 6. For locking the sliding slat in position, a spring catch 35 is provided, the catch including a tongue 36 which projects through an orifice in the skeleton cover of one of the halves and is adapted to seat in a notch 37 formed in the edge of the sliding strip, the tongue being provided with a laterally directed extension 38 which is directed to form a helical spring 39 the terminal of which is fixed to the cover. The tongue is furthermore provided with a finger loop 40 by means of which the tongue may be withdrawn against the tension of its spring.

From the above description it will be seen that a collapsible crate is presented which will be rigid when in set up position, may be readily knocked down into collapsed position in minimum time, and will occupy a minimum space when in collapsed position.

What is claimed is:

A knock down crate comprising two halves each including a bottom, ends foldable inwardly upon said bottom, a side foldable upon the collapsed ends, a cover foldable outwardly upon the collapsed side, means for locking said ends and said cover together in set up position, U-shaped guides projecting outwardly beyond the free longitudinal edge of the cover of one of said halves, a slat slidably fitted in said guides, a common strip connecting said guides, hooks carried by the free longitudinal edge of the cover of the other said halves engageable with said common strip, and hinges connecting the bottoms of both halves for folding movement one upon the other.

In testimony whereof we affix our signatures, in the presence of two witnesses.

ERNEST L. MEYER.
ALFRED F. MEYER.
